D. M. WINANS

CONTROL SHUTTER FOR ENGINE RADIATORS

Filed Oct. 15, 1925

UNITED STATES PATENT OFFICE.

DANIEL M. WINANS, OF BINGHAMTON, NEW YORK, ASSIGNOR TO THE BREWER-TITCHENER CORPORATION, OF CORTLAND, NEW YORK, A CORPORATION OF NEW YORK.

CONTROL SHUTTER FOR ENGINE RADIATORS.

Application filed October 15, 1925. Serial No. 62,616.

This invention more particularly relates to improvements in manually operated radiator shields or shutter fronts for motor vehicles, in which a supplemental shutter supporting frame is adapted for attachment to or removal from the engine radiator without requiring constructive changes in existing cars. One of its objects is to provide a simple, durable and compact apparatus of this character by means of which the temperature of an engine radiator may conveniently be regulated by controlling the air flow through its core opening and thus guard against freezing of the engine cooling medium when used in cold weather. A further object is to provide for an improved shutter adjusting means adapted to be carried up to the instrument board of motor cars for distant actuating purposes.

To this end and the accomplishment of other new and useful results, the invention further consists in novel constructive features, combination and arrangement of its several parts, all of which will be hereinafter more fully described and claimed.

Reference is had to the accompanying one sheet of drawings which are illustrative of a specific embodiment of my invention as applied to motor vehicles, in which like characters of reference indicate like parts in the several views, and in which drawings:

Fig. 1, is a vertical elevation in partial section showing a general arrangement of my shutter frame applied to the front face of an automobile radiator and also the hand operated actuating means therefor.

Fig. 2, is a fragmental enlarged vertical sectional detail taken through the upper portion of the assembled shutter frame with the slats set in open position.

Fig. 3, is a view similar to Fig. 2, but showing the shutter slats drawn into closed position.

Fig. 3^a, represents a transverse fragmental section as taken on line 3^a—3^a, Fig. 3, to show the assembled tie-bar which interconnects the shutter arms and serves to move the slats in unison.

Fig. 4, shows a sectional detail of the knob attached to the adjusting end of the shutter actuating linkage, while Fig. 5, is a bottom view thereof.

Referring more particularly to said drawings, A₁ denotes a motor vehicle radiator tank or casing which circumscribes a honeycomb

or other cellular core A₂, said core being of the usual flat type having opposite front and rear faces provided with a plurality of rather closely spaced horizontal openings therethrough in the conventional manner. The shield or shutter frame is preferably mounted in such fashion that the perimeter of its flared flat flange or brim will fit against the front face of the core and substantially cover the plural core openings so as to permit controlling the flow of cooling air through said core.

My assembled shutter frame housing as such, is designated in its entirety by the letter B and is preferably made up of sheet metal sections, comprising two parallelly disposed side-pieces having their respective ends cross connected by two similarly formed end-pieces such as B₁. These sectional or component frame parts constitute an endless rectangular frame housing into which are pivotally mounted a plurality of parallel damper slats or shutters such as C₁, C₂ etc. When closed, the adjacent shutter edges overlap each other as shown in Fig. 3, and these slats may each be equipped with an actuating arm C₁₀ and connected together to move in unison by the tie-bar C₂₃. The topmost of said slats may be provided with a set of rocker levers C₂₂ to which is attached the shutter manipulating linkage which is shown as comprising a two part adjustable actuating rod made up of the sections D₁₁ and D₁₂ while the free or remote end of this rod is carried up through the dash board D₂ and may be slidably supported by means of an escutcheon plate attached to the instrument board D₂ as indicated in Fig. 1.

To the end that my shutter as attached to the front face of the radiator, may readily be fitted for manipulation from the rear thereof, said actuating rod D₁₁ is slidably mounted to operate through a suitable radiator core hole and the forward end of said rod is operatively connected to rock one or both of said levers C₂₂ in an improved fashion. For this purpose, the complementary spaced rocker levers C₂₂ may be used and for sake of obviating separate fulcrum means therefor, such bracket is preferably attached to rock with the uppermost slat C, as shown. The common fulcrum axis of said levers is intended to align with the respective parallel slat pivots and between these levers is mounted an elongated pin C₂₁.

The aforesaid shutter actuating linkage

may further comprise a relatively narrow link D_{10} whose one eye may be shiftably fulcrumed upon the relatively long pin C_{21} so as to allow of considerable lateral sliding movement thereon. The other eye of said link may be made to engage with the hook end D_{15} bent up from the link end of the push rod D_{11} . The push rod as a whole may be made in two overlapping parts, one being the link rod D_{11} and the other a knob rod D_{12} , the respective sections being secured together by the adjusting clamp D_{13} .

It is expedient to place the control or knob end of the combined push rod some distance above and away from the radiator and in present instance, this is accomplished by kinking each of the rods as shown in Fig. 1 and bringing the two opposite rod ends back into substantial alignment. The movement of the link end of rod D_{11} may be constrained and made to slide through a suitable horizontal hole in the core A_2 which is preferably reenforced by the guide bush D_{14} , thus protecting the adjacent core walls against wear and causing the rod hook D_{15} to travel normal to the vertical front face of radiator core. When the shutters are opened, the link D_{10} as shown in Fig. 2, preferably assumes a position of substantial alignment with respect to its adjacent rod axis while when the shutters are closed, the link is allowed to drop slightly as shown in Fig. 3. The swivel action on part of the link D_{10} allows of considerable vertical latitude in the selection of the most suitable core hole opening for mounting the bush D_{14} while the free lateral movement of the link on the pin C_{21} further facilitates the finding of such a core hole as measured in a horizontal direction, thus affording universal freedom to rod alignment with respect to the encircling walls of the particular core aperture through which the rod slides.

In order to provide for properly holding the shutters in any desired intermediate position, the free end of the rod D_{12} is provided with a series of closely spaced notches D_{24} intended to engage with the sharpened wedge D_{25} preferably formed in the bottom edge of the escutcheon hole D_{20} . The adjusted rod notches may be held in engagement with the wedge D_{25} by means of a Z shaped spring clip D_{26} and one flange end of such a clip may be mounted against the board D_2 and secured thereto by means of the escutcheon plate screws D_{19} while the outer or free end of the clip resiliently bears down upon the rod D_{12} . For the purpose of changing the shutter ad-

justment, the knob is raised slightly against the clip thrust, which in turn disengages the rod notch out of the wedge D_{25} and permits the rod D_{12} to be freely shifted into another notch position.

It is believed that the mode of operation of my shutter devices as applied to a radiator will readily be understood since its purpose and function has now become well known to automobile users, and it will be obvious that the described actuating rod is intended to rock all of the shutter slats in unison. The use of my improvements makes it possible to fit any shape or size of radiator front for practically all leading makes of cars encountering undue difficulty in applying the described style of slat actuating device for rear control from the dash.

It will be understood that various changes in the details and arrangement of my devices may be resorted, all without departing from the spirit and scope of my invention heretofore described and more particularly pointed out in the appended claims.

Claims:

1. A shutter apparatus arranged to control air flow through an engine radiator core, comprising a frame serving to house a plurality of shutter slats adapted to swing between open and closed positions, tie-bar means interconnecting the several slats, slat actuating means including an elongated link pin operatively connected to rock in unison with the slat movements, said actuating means further comprising a reciprocative push rod having one end provided with an intermediary link adapted to pivotally engage and slide lengthwise of said pin, and guide means associated with said radiator core serving to constrain lateral movement on part of the link end of said rod.

2. A shutter apparatus arranged to control air flow through a cellular engine radiator core, comprising a frame serving to house a plurality of shutter slats adapted to swing between open and closed positions, tie-bar means interconnecting the several slats, and slat actuating means including a link pin mounted upon one of said slats together with a reciprocative push rod extending through one of the core cells and of which rod one end is pivotally connected to said pin through the medium of a link.

In testimony whereof, I have herewith set my hand this 13th day of October, 1925.

DANIEL M. WINANS.
